UNITED STATES PATENT OFFICE

ANTON SZELIGA, OF NEW YORK, N. Y., ASSIGNOR OF ONE-HALF TO FREDERICK TICHY, OF NEW YORK, N. Y.

SAFETY ATTACHMENT FOR MOVING PICTURE APPARATUS

Application filed April 23, 1931. Serial No. 532,333.

My invention relates to an attachment for moving picture apparatus, and more particularly to such devices as are used in conjunction with the projecting machine to prevent fires or explosions due to the inflammability of the film employed in said apparatus.

As is known, films used in combination with moving picture exhibiting machines are highly inflammable, and, as a general rule, fires which have taken place in moving picture theaters or halls where such exhibitions take place originated in the picture exhibiting machine itself, the film having been inflamed either by the source of light employed in the machine or by external means through the neglect and carelessness of the operator.

The objects of the present invention are, to provide an attachment of the character above described capable of being manufactured at a low cost and which can be easily, quickly and cheaply applied to all the standard and existing forms of moving picture exhibiting machines, and at the same time will be fool-proof, positive and unfailing in its operation, and as soon as the film becomes ignited automatically severs the same and instantaneously cuts out the burning section of the film and stops the motor actuating the film feeding mechanism, thereby preventing the spread of the fire to the severed and separated portions of the unwound and rewound pictures of the film and other inflammable portions within the operator's booth.

Another object of the invention is to construct and arrange the different elements comprising the attachment whereby the actuating parts are held in the operative and proper position and the film is properly adjusted and threaded through the exhibiting machine only when the energizing electrical current is properly passing through the mechanism on a closed circuit, thereby eliminating all questions of personal equation, and assures that the safety attachment will perform its functions under all conditions for which it is designed independent

of the failure of proper inspection and adjustment of the machine by the operator.

A further object of the invention is, to construct and arrange the different elements comprising the attachment in such a manner that it may be operated in connection with either direct or alternating current without change, substitution or alteration of parts, by the simple operation of a single switch operating mechanism.

Other objects and advantages of applicant's invention will appear from the detailed description of the several parts, the mode of assembling the same and manner of cooperation to be presently explained.

The invention consists of structural characteristics and relative arrangement of elements to be hereinafter more fully disclosed and particularly pointed out in the appended claims.

In the three sheets of drawings, in which similar reference characters indicate the same parts in the several figures:

Figure 1 is a side elevation, somewhat diagrammatic in nature, of sufficient of a picture projecting machine to illustrate the manner in which this invention is adapted thereto;

Figure 2 is a side elevation, partly in section and on a larger scale than Figure 1, showing the upper member of the mechanism constituting this invention;

Figure 3 is a top plan view of the parts shown in Figure 2;

Figure 4 is an opposite side elevation showing the lower member of the mechanism;

Figure 5 is a top plan view of the parts shown in Figure 4; and,

Figure 6 is a diagrammatic view of the electrical circuit system employed in connection with this invention.

Referring, in the first instance, to Figure 1 of the drawings, there is shown of a picture projecting machine the upper film magazine 10, the lower film magazine 11 and a portion of the illuminating lantern 12.

The film F in its passage from the magazine 10 to the magazine 11 and in the path of the light beam b from the lantern 12 is

engaged by various guide and feed rollers, in a manner to be hereinafter more fully described, and passes through a box-like structure comprising a central casing 13, 5 and upper casing 14 having a door 14', and a lower casing 15 having a door 15'. The upper casing contains the cutter mechanism adapted to act upon the film at a point adjacent the upper magazine 10, which mechanism is illustrated in detail in Figures 2 and 3; and the lower casing contains similar mechanism adapted to act upon the film adjacent the lower magazine 11, and which is illustrated in detail in Figures 4 and 5. 10 Referring now to Figures 2 and 3, there is shown a box-like member 16, which is to be mounted between the magazine 10 and the central casing 13, Figure 1. The film F passes through a slot 16^a in the upper member of this structure, being engaged on opposite sides thereof by feed rollers 17, 17, and guide rollers 18, 18, and looped in chamber 16^b, as shown in Figure 2. 15

Laterally projecting from and in horizontal alinement with the top face of the upper member of the box 16 is a plate 19, upon the upper face of which is slidably mounted a blade 20, the inner edge of which is a knife edge 21, and the outer edge of which has secured to it an extrusion 22 terminating in a finger ring 23. 20

Projecting laterally and upwardly from the member 22 is a standard 24, upon which is pivotally mounted a lever 25, the inner end of which is connected by means of a coiled spring 26 with a post 27 upstanding from the plate 19. The outer end of the lever 25 is in the form of a hook 28 adapted to be engaged by a trigger 29, upon a lever 30 pivotally mounted at 31. The lever 30 constitutes the armature for a magnetic coil 32 and, when the latter is energized, is held in the position shown. 35

Mounted upon an insulated plate 33 above the plate 19 is a double pole switch 34 and a pair of resistance coils 35. The switch 34 is adapted to accommodate either direct or alternating current, and the wiring system is such that when the switch is thrown to one pole, when alternating current is employed, it passes directly to the coil 32. When, on the other hand, direct current is employed and the switch is thrown to the other pole, the current passes through the resistance coils 35 before reaching the magnetic coil 32. 40

The blade 20 is longitudinally guided by means of a block 36 secured to the plate 19 and disposed within a longitudinal slot 37 in the blade 20. To the upper face of this block 36 is secured a spring 38 adapted to bear against the blade 20 and maintain it in contact with the plate 19 and prevent jumping or vibration. 45

Above the box-like structure 16 and in

communication with the interior thereof is another box-like structure 39 above and in communication with chamber 16^b and within which are mounted a pair of thermostatic bars 40, which are included in the wiring system of the device. In order that these bars may be conveniently applied and replaced, the box 39 is provided with a detachable lid 41. 70

Contained within the lower casing 15, Figure 1, is a duplicate knife and control mechanism, which is illustrated in detail in Figures 4 and 5. The mechanism, in this case, is mounted upon a plate 19^a, which is secured within the lower portion of the casing 15. 75

Herein, the film is adapted to pass through a slot 19^b in the plate 19^a and to be engaged by a feed roller 17^a and guide rollers 18^a, and from hence it passes into the magazine 11, Figure 1. 80

Referring now to Figure 6, wherein is shown the wiring plan employed in connection with this invention, the various electrical elements are shown. Current, either direct or alternating, is supplied from a power line 42, 43, and the circuit is established and controlled by means of a master switch 44. When alternating current is being employed, the upper and lower double pole switches 34 are thrown to the A. C. pole and the circuit is established through the master switch 44, the lower switch 34, the lower magnetic coil 32, the upper switch 34, the thermostatic bars 40, the upper magnetic coil 32, and back through the master switch 44 to the power line. 90

In the event that direct current is being employed, the double pole switches 34 are thrown to their D. C. poles and the established circuit is through the master switch 44, the lower switch 34, the lower pair of resistance coils 35, the lower magnetic coil 32, the upper switch 34, the upper pair of resistance coils 35, the thermostatic bars 40, 100 the upper magnetic coil 32, and back through the master switch 44 to the power line. 110

The operation of the device is as follows:

The double pole switches 34 are first 115 thrown to accord with the variety of current being supplied and the master switch is then closed, establishing the circuits.

The finger rings 23 are then grasped and pulled outwardly. As each one is withdrawn, the plate 22 and blade 20, with attendant parts, are retracted against the action of the spring 26 until the hook 28 on the lever 25 is pulled clear of the trigger 29 on the lever 30. This lever, constituting the 125 armature for the magnetic coil 32, is maintained in position thereby and the hook 28 is permitted to engage and be retained in retracted position by the trigger 29.

As soon as both the upper and lower ele- 130

ments have been properly adjusted, or "set", in this manner, the film is threaded from the upper magazine 10 through the casings 14, 13 and 15 past and between the various 5 feed and guide rollers, and engaged with the reel in the lower magazine 11. Projection of the picture may then proceed.

In the event that the film catches fire in its exposed position within the casing 13, it 10 is essential that the blazing portion be instantly severed from adjacent portions so that fire be prevented from entering either of the film magazines.

As soon as a fire starts inside the casing 15 13, the heat from it passes upwardly through the box-like structure 16 into the chamber 16^b, enclosed by the structure 39 and lid 41, and acts therein upon the thermostatic bars 40. These are of such predetermined sensitivity that they are immediately warped or bent, and the electrical circuit therethrough is thus destroyed.

The magnetic coils 32 being thereby de-energized release their armatures, the levers 25 20 and 30, and under the action of the coiled springs 26 the hooks 28 on the levers 25 are freed from engagement with the trigger 29 on the levers 30 and the blades 20 shoot forward. Their knife edges 21 sever the film 30 and, under the pressure of the springs 38, the blades are held firmly against the respective plates 19 and 19^a covering the slots therein through which the film normally passes.

35 This entire series of operations takes place substantially instantaneously and the blazing section of film is permitted to burn itself out within the casing 13, making it impossible for the fire to spread into either 40 of the film magazines.

When the thus localized fire is over, the inside of the casing 13 is permitted to be cooled and cleaned, a new pair of thermostatic bars 40 is inserted in place, if found 45 necessary, the cutting mechanisms are reset, the film is again threaded through the rollers, united at its cut ends, and the projection proceeds.

It is, of course, to be understood that 50 various changes and alterations may be made in the mechanical details of structure and arrangement of parts without departing from the spirit of this invention. Such changes will readily suggest themselves to 55 those skilled in the art and require no specific illustration or description. They are to be understood as contemplated within the invention insofar as they fall within the scope of the appended claims.

60 What I claim is:

1. In a film cutting device, the combination of a slotted base plate, means for feeding a film through said slot, a cutter reciprocally mounted upon said base plate, a pivotally mounted lever carried by said cutter,

spring means engaging one arm of said lever and tending to maintain it in one extreme position and with said cutter projected across the slot, means for retracting said cutter against the action of said spring 70 means, an electric magnetic coil, a pivotally mounted armature therefor cooperating with said lever to maintain said cutter in retracted position when said magnetic coil is energized, and thermostatic means for controlling the supply of current to said magnetic coil.

2. In a film cutting device, the combination of a slotted base plate, means for feeding a film through said slot, a cutter reciprocally mounted upon said base plate, spring means for projecting said cutter across the slot, means for retracting said cutter against the action of said spring means, means for retaining said cutter in a retracted position, 80 electric means adapted to be operated by either direct or alternating current for actuating said retaining means, a double pole switch to select the electric circuit to be employed, and thermostatic means for controlling said electric means.

3. In a film cutting device, the combination of a slotted base plate, means for feeding a film through said slot, a cutter reciprocally mounted upon said base plate, spring means for maintaining said cutter in operative engagement with said base plate, spring means for projecting said cutter across the slot, means for retracting said cutter against the action of said second named spring 95 means, means for retaining said cutter in a retracted position, electric means for actuating said retaining means, and thermostatic means for controlling said electric means.

4. In a film cutting device, the combination of a slotted base plate, means for feeding a film through said slot, a cutter reciprocally mounted upon said base plate, a lever pivotally mounted upon said cutter, a spring having one end secured to said base plate and the other end secured to one arm of said lever, a hook on the other arm of said lever, means for retracting said cutter against the action of said spring, a trigger adapted to engage said hook to maintain said lever in position to retain said cutter in a retracted position, electric means for actuating said trigger, and thermostatic means for controlling said electric means.

5. In a picture projecting machine, the combination of upper and lower film magazines, means for guiding a film therebetween, an enclosure for said film guiding means, spring actuated means within said enclosure for cutting the film, a hook pivoted on and moving with said spring actuated means, means externally of said enclosure and attached to said spring actuated means for setting said cutting means, an electric circuit, an armature locked into engaging 120 125 130

position with said hook by said electric circuit for retaining said cutting means in an inoperative or set position, and thermostatic means for interrupting said electric circuit and releasing said locked armature.

6. In a film cutting device, the combination of a slotted base plate, means for feeding a film through said slot, a cutter reciprocally mounted upon said base plate, spring 10 means for projecting said cutter across the slot, means for retracting said cutter against the action of said spring means, a pivotally mounted lever provided with a hook at its free end and carried by and moving with 15 said cutter, an electro-magnet having a pivotally mounted armature supported by said base plate and adapted to engage with said hook of first named lever to retain said cutter in retracted or inoperative position, an 20 electric circuit for energizing said electro-magnet and holding said armature and hook in engagement, and thermostatic means controlling said electric circuit.

7. In a picture projecting machine, the 25 combination of upper and lower film magazines, means for guiding a film therebetween, means for cutting the film at a point adjacent the upper magazine, means for cutting the film at a point adjacent the 30 lower magazine, means for retracting each of said cutting means, an electrically energized means for retaining each of said cutting means in a retracted or inoperative position, an electric circuit for actuating or 35 energizing each of said retaining means, an alternate current pole or terminal, a direct current pole or terminal connected with said electric circuit, a resistance interposed between the direct current pole and said 40 electric circuit, a double pole switch for each of said electric circuits and cooperating with said alternate or direct current pole to select the electric current to be employed, and a single thermostatic means connected 45 in the electric circuit for simultaneously controlling both of said electrically energized and cutting means.

In testimony whereof, I hereunto affix my signature.

50 ANTON SZELIGA.
